Arthur W. Kimbell

UNITED STATES PATENT OFFICE

1,963,792

VACUUM TUBE SOCKET AND TERMINAL
THEREFORArthur W. Kimbell, Chicago, Ill., assignor to Cinch
Manufacturing Corporation, Chicago, Ill., a cor-
poration of Illinois

Application July 5, 1929, Serial No. 375,922

1 Claim. (Cl. 173—328)

My invention is for improvements in socket devices particularly though not exclusively for use as radio tube sockets.

In the drawing accompanying and forming a part of my application: Figure 1 is a plan view of a preferred form of socket device; Fig. 2 is an underside view of the socket device; Fig. 3 is an enlarged section taken on the line 3—3 on Figure 1; and Fig. 4 is a plan view of a terminal member for the socket showing the rivet-like attaching means.

While I have illustrated in the accompanying drawing and will hereinafter describe a preferred embodiment of my invention, I do not wish to be limited thereby because my invention will be best defined in the claim forming a part of my application.

The embodiment of my invention illustrated comprises a single plate 1 of insulating material having a number of apertures 2 arranged in a circle about the center of the plate to receive the prongs or terminals of a vacuum tube (Figure 1) with a terminal member 3 for each aperture secured to the underside of the plate 1, as shown in Figs. 2 and 3.

The terminal members may be of any suitable form, such as shown in my co-pending applications, Serial Numbers 375,923 and 375,924 filed herewith, my invention as to the terminals being in the means for attachment. The particular terminal 3 shown is the same as that illustrated and described in my co-pending application Serial No. 375,924 filed herewith and each has a yieldable sleeve 4, a base 5 and a wiring terminal 6.

Means in the form of attaching portions 7 are pressed from the material of the base 5 at advantageous points for holding the terminal securely in position when attached to the plate 1. In the embodiment of the terminal member selected for illustration I have provided two attaching portions 7. One is located at one edge of the base and the other is located in the base extension between the sleeve 4 and the wiring terminal 6 at the end of the same and both extend in the opposite direction from the sleeve, as shown in Fig. 3.

When the terminal members are attached to the plate 1 the attaching portions 7 pass through apertures previously formed in the plate and have their ends deformed against the upper side, as shown in Figs. 1 and 3. The terminals are so arranged that each has an attaching portion 7 located between the center of the plate and an aperture 2 in the plate, while the other attaching

portion 7 is located outside of the circle of the apertures 2. Thus the thin flat insulating plate is formed with three substantially concentric series of apertures, with the apertures of each series equal in number to the others, and with the apertures of the adjacent series forming triads, the intermediate aperture of which is the prong-receiving aperture, while the end apertures of the triads receive the lugs or attaching portions 7.

If a washer 8 of insulating material is attached to the upper face of the plate 1, as illustrated, to provide a guide for aiding in registering the contacts of a tube with the apertures 2 it will cover the attaching portions 7 located inside the circle of apertures, concealing the same and preventing loosening of the same or accidental short circuiting of a tube. As will be clear from the drawing, the attaching portions 7 located inside the circle of apertures are preferably disposed as shown, to lie closely adjacent the wiring terminal end of the base extension to support it against bending, and with the spacing therebetween exceeding the distance between the vacuum tube prongs, these ends being attained with a minimum of material by striking the outer tongue 7 upwardly and outwardly with reference to the aperture in the terminal base, as best shown in Fig. 4.

In the type of socket illustrated it is desirable to provide terminal members which have means for making a tight gripping contact with the prongs of a tube. Therefore it is desirable, especially where only one plate is used, to hold the base 5 securely against the underside of the plate to maintain the sleeves 4 in proper alignment with the apertures 2. By securing the terminals in the manner described and illustrated the terminals 3 are prevented from becoming distorted as well as from being turned.

The device which I have illustrated and described is reduced to a minimum number of parts which may be manufactured with ease and at a relatively low cost and can be easily and quickly assembled.

I claim:

A radio tube socket of the type embodying a single thin flat plate of insulating material having a series of tube-prong-receiving apertures arranged in a circle about the center of the plate and having prong-engaging terminals carried by the plate in alignment with its apertures, said tube socket having the following improved construction: said plate having in addition to said series of prong-receiving apertures, two series of lug-receiving apertures, each equal in number

to the series of prong-receiving apertures, and one series located substantially concentrically inwardly of said prong-receiving apertures, and the other substantially concentrically outwardly thereof, thus forming similar triads of apertures with a prong receiving aperture as the intermediate member of each triad; said terminals each consisting of a base having a prong-aperture therethrough and having contact fingers integral 10 with its base forming a contact sleeve extending downwardly from the plane of its base and in alignment with the prong-aperture in its base, said terminals each further comprising an extension, in the plane with its base, terminating in 15 a wiring connection, and said terminals each being formed with two integral attaching-lugs extending upwardly from the plane of its base and passing into the end apertures of the triads, respectively, locating the prong-apertures in the terminal bases in alignment under the prong-receiving apertures of the thin flat plate, one of said attaching lugs being stuck out of said base-extension, and said attaching lugs extending through said thin flat plate and having their extending ends deformed to secure the terminal members firmly in aligned position against the underside of said plate, and said socket further embodying a guide-disc secured 80 concentrically within the circle of tube prong receiving apertures and covering the deformed ends of the attaching-lugs extending through the inner series of lug-receiving apertures, thus isolating the same from observation and from engagement by the prongs of a vacuum tube. 85 90

CERTIFICATE OF CORRECTION.

Patent No. 1,963,792.

June 19, 1934.

ARTHUR W. KIMBELL.

It is hereby certified that error appears in the printed specification of the above numbered patent requiring correction as follows: Page 1, line 74, for "inside" read outside; page 2, line 79, the claim, for "stuck" read struck; and that the said Letters Patent should be read with these corrections therein that the same may conform to the record of the case in the Patent Office.

Signed and sealed this 7th day of August, A. D. 1934.

to the series of prong-receiving apertures, and one series located substantially concentrically inwardly of said prong-receiving apertures, and the other substantially concentrically outwardly thereof, thus forming similar triads of apertures with a prong receiving aperture as the intermediate member of each triad; said terminals each consisting of a base having a prong-aperture therethrough and having contact fingers integral 10 with its base forming a contact sleeve extending downwardly from the plane of its base and in alignment with the prong-aperture in its base, said terminals each further comprising an extension, in the plane with its base, terminating in 15 a wiring connection, and said terminals each being formed with two integral attaching-lugs extending upwardly from the plane of its base and passing into the end apertures of the triads, respectively, locating the prong-apertures in the terminal bases in alignment under the prong-receiving apertures of the thin flat plate, one of said attaching lugs being stuck out of said base-extension, and said attaching lugs extending through said thin flat plate and having their extending ends deformed to secure the terminal members firmly in aligned position against the underside of said plate, and said socket further embodying a guide-disc secured 80 concentrically within the circle of tube prong receiving apertures and covering the deformed ends of the attaching-lugs extending through the inner series of lug-receiving apertures, thus isolating the same from observation and from engagement by the prongs of a vacuum tube. 85 90
